UNITED STATES PATENT OFFICE.

WILLIAM H. CROSS, OF DAYTON, OHIO.

PUMP CONSTRUCTION.

968,029.

Specification of Letters Patent. Patented Aug. 23, 1910.

Application filed May 3, 1910. Serial No. 559,142.

To all whom it may concern:

Be it known that I, WILLIAM H. CROSS, a citizen of the United States, residing at Dayton, in the county of Montgomery and State 5 of Ohio, have invented certain new and useful Improvements in Pump Constructions; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to certain improvements in pump construction.

The object of the invention is to provide a pump which is devoid of the usual packing. To this end the pump is provided with 20 an inner removable cylinder in which the piston moves. This inner cylinder coöperates with other parts of the pump, at both ends, to form tight joints without the use of any of the well known forms of packing usually 25 found necessary to employ in a variety of pumps.

In the accompanying drawing consisting of a single vertical sectional elevation of the pump, the invention is clearly illustrated 30 and in connection with a description of the pump, various well known features will be incidentally referred to.

The outer cylinder 1 or pump casing, comprises a casting which may be made of any 35 suitable metal to meet the requirements. One end of said pump casing is provided with a screw threaded aperture of reduced diameter as compared with the diameter of the pump casing, and the other end of the 40 casing terminates in the same diameter as the body portion of said casing and is provided with screw threads for the attachment of an apertured member 3 which is also screw threaded to connect with the inlet pipe 45 4, the outlet pipe 5 connecting with the other end of the pump casing just described. The upper end of the pump casing 1 on the interior thereof, is provided with an annular shoulder 2^a by machining the same, and in 50 the lower end of said pump casing resting upon the member 3 is a disk 8. 2 designates an interior cylinder or removable lining one end of which engages the shoulder 2^a in the upper end of the pump casing and the lower 55 end of which engages the upper side of the disk 8 at the point 2^b. By screwing the

member 3 into the lower end of the pump casing, the ends of the cylinder 2 are brought in rigid contact with the shoulder 2^a and the disk 8 and the effect of a tight joint is thus 60 secured at each end of the inner cylinder and between said inner cylinder and the pump casing which dispenses with the necessity of employing any other packing.

It will be understood that the shoulder 2^a, 65 disk 8 and the ends of the cylinder 2 are suitably faced to provide for a close even contact between the several parts. The upper end of the cylinder is held in position by the surrounding surface 1^a of the pump 70 casing, and the lower end of said cylinder is similarly held in position by a surrounding portion 1^a which is in alinement at all points with the upper surface 1^a. The lower inlet valve 6^a seats upon the surrounding 75 portion of the member 3, which portion is suitably faced to provide a seat for said valve. The said valve 6^a has as integral parts thereof the usual wings 6 which form 80 guides for the movement of the valve, and the disk 8 is provided with a suitable number of guides 7 projecting from its lower face within which said valve 6^a moves when drawn from its seat by the upward movement of the piston. The piston consists of 85 a spider 13 which terminates in an annulus 11, and a ring 10 which has a screw threaded engagement with said annulus, and between these parts suitable packing 12 is secured to 90 effect a proper joint between the piston and the cylinder 2. The outlet valve 9 is in closed within the arms of the piston and seats upon the portion 10 of said piston, said valve having the usual form of wing guides 95 which project through an axial opening in the lower part of the piston and into an axial opening in the disk 8 before referred to. The usual piston rod 14 extends from the piston to the exterior of the pump where it is provided with any suitable power connection (not shown).

Having described my invention, I claim:

In a pump, in combination, a casing provided on the interior of its upper end with a faced shoulder and an annular surface below said shoulder lying inwardly from the interior surface of said casing, the lower end of said casing being provided with a similar annular surface in alinement with the upper annular surface, a member united 105 to the lower end of said pump casing, a disk supported upon said member, and an inner 110

cylinder or lining the upper end of which engages the shoulder in the upper end of the cylinder and the surrounding annular surface below said shoulder, and the lower 5 end of which engages the upper side of said disk near the circumference thereof and the inwardly projecting annular surface on the interior of the pump casing, the ends of said cylinder or lining so engaging the shoulder 10 on the upper end of the pump casing and

the said disk, effecting a tight joint at both ends of the cylinder, and a piston and valves operating substantially as specified.

In testimony whereof I affix my signature, in presence of two witnesses.

WILLIAM H. CROSS.
